UNITED STATES PATENT OFFICE.

COURTNEY M. JENKINS, OF WASHINGTON, DISTRICT OF COLUMBIA.

STREET-RAILWAY TRANSFER-TICKET.

1,167,566.

Specification of Letters Patent. Patented Jan. 11, 1916.

Application filed May 4, 1915. Serial No. 25,774.

To all whom it may concern:

Be it known that I, COURTNEY M. JENKINS, a citizen of the United States, residing at Washington, in the District of Columbia, 5 have invented new and useful Improvements in Street-Railway Transfer-Tickets, of which the following is a specification.

This invention relates to a new and improved street railway ticket, and one of its 10 objects is to provide a ticket having a time period limit and which will automatically indicate when the time limit has expired and the ticket is void for use.

Another object of the invention is to provide a transfer ticket which obviates the necessity of using a time table and the necessity of punching the transfer to show the time limit.

A still further object of the invention is 20 to provide a transfer ticket which is also adapted for use as an effective advertising medium.

In the accompanying drawing,—Figure 1 is a face view of one form of transfer ticket 25 embodying my invention. Fig. 2 is a view of the same as it appears when void for use. Fig. 3 is a view of the same transfer when void, and illustrating a modification. Fig. 4 is a view, like Fig. 3, of the same transfer 30 with a different kind of sympathetic appearing subject matter.

Referring now particularly to Figs. 1 and 2 of the drawing, 1 designates a transfer ticket of suitable size and shape and made 35 of paper or other suitable material. This transfer ticket may bear upon its face any suitable printed matter indicative of its character. For instance, the printed matter may consist of the name or title of the rail- 40 way company, together with any informative matter indicatory of the character and purpose of the ticket. The ticket may also and preferably will bear, as shown a suitable warning notice that it has a time period 45 limit and must be used within such period, after being tendered to the holder, or that it will be void for use as a transfer. The printed matter referred to may be printed in an ordinary or permanent ink or in a 50 fugitive ink which disappears after having been exposed to light for the given period constituting the time limit for which the transfer ticket is valid. In Figs. 1 and 2 the printed matter disclosed is designed to be of 55 a permanent character, but the ticket 1 shown therein is provided with indicating

means of a nature influenced by light, by means of which the transfer is rendered invalid for use at the expiration of its time limit period. This indicating means consists, as indicated in dotted lines in Fig. 1, of a suitable word or sign, such as the word "Void" printed in a sympathetic ink of a character which is normally invisible but which, when exposed to light for a given 60 period, will be rendered visible. This indicating word is preferably designed to be printed in ink of a color contrasting with that of the title and other informative printed matter so as to be clear and distinctive 65 in appearance when fully developed by the action of light.

In practice the transfer tickets may be put up in pad or other suitable form, contained in a light-proof package from which 70 the tickets may be individually dispensed, so that they will be unaffected until removed from the package or exposed to light, the time period beginning at the moment the transfer is withdrawn from the packet and 75 dispensed. Thus the holder of the ticket will be provided with a ticket which is good 80 for transfer from one railway line to another during a certain period, the expiration of which will be shown by the appearance 85 of the word "Void," as shown in Fig. 2, in full volume and color, at which time and when appearing in such condition the transfer becomes null and void. It will be understood that the indicatory matter in sympathetic 90 ink will gradually appear and its color tone will develop in a progressive manner, so that the age of the transfer, at any time between its issuance and expiratory period, may be determined at a glance. For 95 the purpose of preventing any mistake or misunderstanding there may be printed or otherwise provided upon the ticket a comparison mark 3, such as a solid block printed in a permanent ink of the color the indicatory matter should have when fully developed.

If desired, the title and informative matter upon the ticket may be printed in a fugitive or disappearing ink, which disappears entirely as the indicatory matter appears, as is indicated by the ticket 1^a in Fig. 3, which shows the ticket in the condition it appears when void, the informative matter having disappeared and the indicatory 105 matter having developed in full.

The indicatory matter used in connection

with informative matter of either a permanent character, as shown in Figs. 1 and 2, or of a fugitive character, as shown in Fig. 3, may be varied to a considerable extent. 5 For instance, it may be in the nature of advertising matter, as shown in the ticket 1^b in Fig. 4, which is printed in sympathetic ink and appears or is developed by light so as to show at the expiration limit. It is 10 preferable, however, to use an appearing advertisement in connection with disappearing informative matter, as at the end of the expiratory period all matter indicating the original nature of the ticket as a transfer 15 ticket is obliterated and the ticket appears simply as an advertising slip, but, of course, it is to be understood that such sympathetic advertising matter may be used in connection with permanent informative matter 20 with any suitable additional advice or information that may be required.

As a further modification of my invention I may provide a transfer ticket which bears thereon all of the matter indicating its nature in a fugitive or disappearing ink, which at the end of the time period for which the transfer is valid entirely vanishes, leaving the holder with a blank slip of paper which has no value whatever as a transfer ticket. 25 These and other modifications of equivalent character are held to fall within the spirit and scope of my invention.

It will thus be seen that the invention provides a transfer ticket which will be affected 30 by light, immediately upon its removal from the dispensing packets, or otherwise be affected upon its removal from the packet, so that at the end of a designated time period it will automatically render 35 itself null and void. This dispenses with the necessity of numbering the transfers, or of printing time tables thereon, or even of printing different transfers for different lines, and it also obviates the necessity as 40 well as the loss of time incident to punching the transfer to indicate the time limit, resulting in decreased labor on the part of the conductor and the saving of time and the handling of passengers at crossing points 45

with greater facility. Other advantages of 50 the invention will be apparent from the foregoing description.

The sympathetic ink employed in printing the indicatory matter may in some cases be of a kind which will not normally be affected 55 by light, but may be made sensitive to light at the moment of dispensing it from the packet by bringing it into contact with a substance or surface which will physically or chemically change it to render it sensitive 60 to light.

I claim:—

1. A street railway transfer ticket embodying means influenced by light rays for indicating whether or not the ticket is void, 65 and means upon the ticket for indicating by comparison a condition of the first-mentioned means to indicate the void stage.

2. A street railway ticket provided with normally invisible matter to be developed 70 by light rays, and normally visible matter to be rendered invisible by light rays.

3. A street railway transfer ticket bearing matter adapted to disappear under the influence of light rays, and other matter 75 adapted to appear under the influence of light rays.

4. A street railway transfer ticket bearing thereon matter normally invisible and adapted to be developed by light rays after 80 a predetermined period to indicate that said ticket is void, and a comparison means for indicating when such developed matter is developed to a mature degree.

5. A street railway transfer ticket having 85 means adapted to be influenced by light rays and developed to a predetermined condition to indicate a void period, and a comparison mark upon the ticket of a color conforming to that adapted to be assumed by 90 such means when the void period is reached.

In testimony whereof I affix my signature in presence of two witnesses.

COURTNEY M. JENKINS.
